CARLTON W. CONNER, OF TORONTO, ONTARIO, CANADA, ASSIGNEE OF ONE-HALF TO
WILLIAM LINTON, OF TORONTO, ONTARIO, CANADA.

CIRCULAR METAL ROOF.

1,116,244.

Specification of Letters Patent. Patented Nov. 3, 1914.

Application filed June 22, 1912. Serial No. 705,216.

To all whom it may concern:

Be it known that I, CARLTON W. CONNER, of the city of Toronto, in the Province of Ontario, Canada, have made certain new and useful Improvements in Circular Metal Roofs, of which the following is a specification.

This invention relates particularly to roofs for granaries, silos or other circular structures and my object is to devise a roof which while stiff, strong and weatherproof may be put together with a minimum of labor and that without requiring any special skill on the part of the builder. I attain my object by means of the special arrangement of the apex casting, radial angle bars, roof sections, cap strips and connections herein-after described and illustrated in the accompanying drawings in which—

20 Figure 1 is a view in elevation of a metal granary constructed in accordance with my invention; Fig. 2 is a plan view of the same; Fig. 3 is a plan view partly broken away on an enlarged scale of part of the roof; Fig. 4 is a cross-section of part of the roof partly broken away; Fig. 5 is a plan view partly broken away of the central casting; Fig. 6 is a vertical cross section of the same; Fig. 7 is a cross-section on an enlarged scale of one of the joints of the roof.

25 In the drawings like numerals of reference indicate corresponding parts in the different figures.

30 1 is the wall of the granary, which as usual is formed of corrugated sheet metal. The granary is provided with the usual door 2 and a discharge spout 3.

35 The present invention relates particularly to the roof and it must be understood that the construction I shall describe is well adapted for all forms of circular roofs or sky-lights as well as for granary roofs.

40 The roof supports comprise a series of radial bars 4. To give strength and stiffness these are preferably formed as cross-shaped angle bars preferably formed by bending up sheet metal as shown particularly in Fig. 7. Each angle bar at its outer end has a cast wall bracket 5 riveted thereto. The lower 45 rib of each angle bar, it will be noted on reference to Fig. 4, is cut away to enable the wall bracket to be secured in place.

45 The upper surface of the wall bracket is rabbeted to form the shoulder 6, against which the ends of the lateral flanges of the

angle bar abut. These wall brackets are bolted or otherwise secured to the top of the wall of the granary, as shown in Fig. 4.

50 It is the object to eliminate all fastening bolts or rivets as far as may be possible, and I have devised a special form of connection for the inner ends of the angle bars which entirely dispenses with bolts or fastenings to secure the inner ends of the angle bars in place.

55 The central casting comprises two parts. One part is formed with the collar 7 and the frusto-conical skirt 8, the angle of which corresponds to the desired pitch of the roof. The other part of the central casting is fitted over this and comprises the collar 9 sleeved on the collar 7. Cast with the collar 9 is the skirt 10 which is shaped to form a series of radial sockets 11. It will be noted that the skirt 8 forms the bottom of these parts.

60 The skirt 8 is preferably formed with a series of radial slots 12, to receive the lower flanges of the angle bars, as shown particularly in Fig. 4. If T-bars were employed these slots might be omitted.

65 On each side of each slot I may form lugs 13 to press the lower flanges of the angle bars and to provide means for bolting the angle bars to the skirt 8, if for any purpose it became necessary to do so. In a granary roof however these lugs may usually be dispensed with.

70 It will be seen that when the angle bars are inserted in the sockets 11, and the wall brackets 5 secured to the upper edge of the granary wall, that the angle bars and central casting will be securely held in position, the only bolts required to be placed by the builder being those securing the outer ends of the angle bars to the granary wall.

75 The roof is formed of a series of sector-shaped plates 14, each having its edges turned up to form the flanges 15. The end of each plate is preferably formed with a depending flange 16, which serves to prevent rain or snow being blown into the granary beneath the outer edges of the plates and the edge of the wall of the granary.

80 The roof sections 14 are held in place by means of the cap bars 17, which on reference to Fig. 7, it will be seen, embrace the flanges 15 and the plates of the sections and the upwardly extending flanges of the angle bars.

bars. The edges 18 of the cap bars are preferably turned down, as shown, to engage the roof sections. These cap bars fit into the sockets 11, as shown particularly in Figs. 3 and 4. The lower end of each cap bar has an end casting 19 secured thereto. When the cap bar is in place these end castings are secured to the wall brackets 5 by means of the bolts 20. When these cap bars 10 are in place the roof sections are securely held in place and absolutely water-tight joints are formed where the sections are supported on the angle bars.

When filling a granary it is necessary to 15 remove one or more roof sections. To do this it is merely necessary to remove two or more of the bolts 20, when two or more cap bars 17 and roof sections 14 are easily slipped out and replaced when the granary 20 is to be closed again. It will be noted that the sockets 11 flare so that the angle bars, roof sections and caps are all readily pushed up into place between the skirts while the gradual narrowing of the sockets causes all 25 the parts to be pressed tightly together as the caps are pushed into place. The shoulders 21 on the skirt 10 engage the cap bars, to press their edges tightly against the roof sections. The joints are thus made as 30 secure against rain and fine drifting snow as if soldered. The central opening in the central casting is covered by the ventilator 21 of any desired type.

From the above description it will be 35 seen that I have devised a roof construction which will satisfactorily accomplish the objects of my invention as set out in the preamble to this specification.

What I claim as my invention is:—

40 1. In a sheet metal roof the combination of radial angle bars each having two lateral and one upwardly extending flanges; an apex casting having a tapered socket formed therein to receive the ends of the angle bars to support and be supported 45 thereby; roof sections having their sides supported on the lateral flanges of said angle bars and provided with side flanges adapted to lie against the upwardly extend-

ing flanges of the angle bars; and cap bars 50 fitting over said flanges, having their inner ends received in the sockets of the apex casting whereby the bars are pressed in place against the roof sections and means for securing their outer ends to the angle 55 bars.

2. In a sheet metal roof the combination of radial angle bars each having two lateral and one upwardly extending flanges; wall brackets secured to the outer ends of the 60 angle bars; an apex casting having tapered sockets formed therein to receive the inner ends of the angle bars to support and be supported thereby; roof sections having their sides supported on the lateral flanges 65 of said angle bars and provided with side flanges adapted to lie against the upwardly extending flanges of the angle bars; cap bars fitting over said flanges and having their inner ends received in the sockets of 70 the apex casting; and cap ends secured to the ends of the cap bars and bolted to the wall brackets.

3. In a sheet metal roof the combination of radial angle bars each having two lateral 75 and one upwardly extending flanges; an apex casting having a tapered socket formed therein to receive the ends of the angle bars; roof sections having their sides supported on the lateral flanges of said angle bars and 80 provided with side flanges adapted to lie against the upwardly extending flanges of the angle bars; and cap bars of sheet metal shaped to embrace said flanges, extended laterally at each side, and provided with 85 downwardly turned edges adapted to rest on the upper surface of the roof sections, the inner ends of the said bars fitting into said sockets, whereby the bars are pressed closely 90 against the roof sections; and means securing the outer ends of the cap bars to the angle bars.

Toronto, Ont., this 18th day of July, 1912.

CARLTON W. CONNER.
